UNITED STATES PATENT OFFICE.

JAMES A. FLOMERFELT, OF NEW YORK, N. Y.

DESIGN FOR A CUFF-BUTTON.

SPECIFICATION forming part of Design No. 24,091, dated March 12, 1895.

Application filed October 30, 1894. Serial No. 527,490. Term of patent 3½ years.

To all whom it may concern:

Be it known that I, JAMES A. FLOMERFELT, a citizen of the United States, residing at the city of New York, county and State of New York, have invented a new and useful Design for a Link Cuff-Button, of which the following is a specification.

Reference is to be had to the accompanying drawings illustrating my design, in which—
10 Figure 1 is a side elevation of a link cuff-button embodying the design, and Fig. 2 is a front view thereof.

My design consists essentially in the shank portion 2 of the cuff button having double-inclined or forwardly projecting or converging front or outer edge 1, as combined with, or viewed in connection with, its angularly disposed heads 3, 4 at opposite ends of the

shank, said heads being inclined toward each other from the rear toward the front of the 20 button, whereby the general planes of the heads tend or lean toward the planes of the two adjacent forwardly converging angularly disposed parts of the front edge 1 of the button shank, all as shown more clearly in Fig. 25 1 of the drawings.

What I claim is—

The design for a link cuff-button, substantially as herein shown and described.

In testimony whereof I affix my signature 30 in the presence of two witnesses.

JAMES A. FLOMERFELT.

Witnesses:

ALVIN K. GOODWIN,
JAMES P. J. MORRIS.
